ASH TRAY

Filed Nov. 23, 1942

Cicero E. Connor INVENTOR

BY John W. Hellman

UNITED STATES PATENT OFFICE

135,248

DESIGN FOR AN ASH TRAY

Cicero E. Connor, Dallas, Tex.

Application November 23, 1942, Serial No. 108,852

Term of patent 14 years

To all whom it may concern:

Be it known that I, Cicero E. Connor, a citizen of the United States, residing at Dallas, in the county of Dallas and State of Texas, have invented a new, original, and ornamental Design for an Ash Tray, of which the following is a specification, reference being had to the accompanying drawing, forming a part thereof.

The figure shown is a front perspective view of an ash tray embodying my design.

I claim:

The ornamental design for an ash tray, substantially as shown.

CICERO E. CONNOR.
